E. KÄGI

CONDENSER FOR USE WITH REFRIGERATORS

Filed August 7, 1923

UNITED STATES PATENT OFFICE

EMIL KÄGI, OF WINTERTHUR, SWITZERLAND, ASSIGNOR TO SULZER FRÈRES SOCIÉTÉ ANONYME, OF WINTERTHUR, SWITZERLAND, A CORPORATION OF SWITZERLAND.

CONDENSER FOR USE WITH REFRIGERATORS.

Application filed August 7, 1923. Serial No. 656,191.

To all whom it may concern:

Be it known that I, EMIL KÄGI, a citizen of Switzerland, residing at Winterthur, Switzerland, 122 Jonas Furrerstrasse, have **5** invented certain new and useful Improvements in Condensers for Use with Refrigerators, of which the following is a specification.

This invention relates to condensers more **10** especially adapted for use with refrigerators having a liquefying chamber in the form of a coiled tube, and has for its object to provide in a compact form a condenser having a large cooling surface.

15 The invention consists in the coiled tube being disposed in a cooling water conduit formed between the two parts of a cylindrical double wall. The coiled tube and the cooling water conduit are preferably both **20** in, the form of a cylindrical helix. Conveniently the outer part of the double wall is divided into at least two portions, the inner part preferably being similarly divided.

25 A construction according to the invention is illustrated by way of example in the accompanying drawing, in which

Fig. 1 is a vertical section through the condenser, and

30 Fig. 2 is a horizontal section taken on the line 2—2 of Fig. 1.

The refrigerating medium, which is to be liquefied in the condenser, passes downwards through the helical tube *a*. This tube *a* is **35** disposed within the helical space *d* formed between the inner and outer parts *b* and *c* respectively of a cylindrical double wall. The cooling water is caused to flow upwards through the space *d* past the outside of the **40** tube *a*. Owing to the arrangement of the tubes and to the fact that cooling water is flowing in a direction opposite to that of the refrigerating medium, a very considerable cooling action is obtained.

45 The outer part *c* of the double wall is divided into two portions connected together

by flanges *e*, to facilitate assembling the condenser and opening up the cooling water passage *d* for cleaning purposes. The inner part *b* of the wall may be similarly subdivided if desired. **50**

It will be understood that although the condenser according to the present invention has been described primarily with reference to its employment with a refrigerator, **55** it may be employed for other purposes if desired.

I claim:

1. A condenser especially adapted for use with refrigerators comprising a coiled tube, **60** and a cylindrical double wall casing enclosing said tube, the walls of said casing forming a helical conduit in which said coiled tube is disposed, so as to leave a fluid circulating passage between the interior surface **65** of said helical conduit and the exterior surface of said tube, and the inner and outer walls of said casing being separable from the coil.

2. In a condenser especially adapted for **70** use with a refrigerator the combination of a cylindrical double wall and a cooling water conduit formed between the two parts of the cylindrical double wall with a liquefying chamber in the form of a coiled tube cylindrically bent and disposed in the cooling **75** water conduit, the outer part of the double wall being divided into at least two portions.

3. In a condenser especially adapted for **80** use with a refrigerator the combination of a cylindrical double wall and a cooling water conduit formed between the two parts of the cylindrical double wall with a liquefying chamber in the form of a coiled tube **85** cylindrically bent and disposed in the cooling water conduit, the inner part of the double wall being divided into at least two portions.

In testimony whereof I have affixed my **90** signature.

EMIL KÄGI.
